JOHN HENRY WELLER, OF PERTH AMBOY, NEW JERSEY, ASSIGNOR TO THE BARBER ASPHALT COMPANY, OF PHILADELPHIA, PENNSYLVANIA, A CORPORATION OF WEST VIRGINIA

SHINGLE

Application filed September 30, 1924. Serial No. 740,689.

This invention relates to shingles and it is more particularly concerned with improvements in that type—commonly denominated flexible—fabricated from a suitable material 5 impregnated with preservative solution impervious to moisture and coated on one or both faces with mineralized surfacing.

Shingles of the foregoing typified character are very difficult to apply with regularity and 10 precision, especially by inexperienced labor, unless the roof or other surface to which they are to be attached is previously marked with proper guide lines. Even when so marked it is common knowledge that very few workmen avail themselves of such guide lines, consequently much time and unnecessary expense is wasted, while the finished appearance is frequently inelegant and unsatisfactory.

An object of this invention is to overcome 20 the above stated disadvantages in a simple and effective manner by configuring the individual shingles or shingle lengths so that the upper portion thereof serves—or functions—as a guiding means for consecutively 25 laid units and succeeding rows thereof, whereby regularity in lining of the finished surface automatically results.

Another object associated with my invention is the economical provision of a shingle 30 or shingle length which, when laid, affords a uniform multi-ply surface that is weather-bound in a novel manner while of a character to withstand wind disturbance, driving storms and other climatic agencies productive of inequalities in continued compactness of the exposed surface.

Other objects and attendant advantages accruing to this invention will be later on referred to, or become apparent, from the following description of practical embodiments 40 thereof, reference being had to the accompanying drawings, constituting a part of this specification, and in which like indices are employed to designate the same or corresponding parts in all the views.

Fig. I is a face view of a fragmentary portion of a roof or other surface having shingles in accordance with this invention applied thereto.

Fig. II is a sectional end view looking to-

ward the left-hand of the preceding figure.

Fig. III is a plan view of an individual shingle scored at its tip for retroversion, as well as illustrating the manner in which said shingle is cut from strip material without 55 waste.

Fig. IV is a similar view of a slightly modified form of the invention devised to ensure adhesion between successively laid rows thereof; and,

Figs. V and VI are plan views indicative of the economical saving effected when cutting shingles in accordance with the present improvements from standard widths of sheet material.

Generally considered, and before proceeding with a detailed description of the drawings, my improved shingles or shingle strips are manufactured from sheet felt impregnated with asphaltum and surfaced on one 70 or both faces with crushed slate or other desired mineral substance, in accordance with well known methods prevailing in the art. Material of the typified nature is usually made in standard widths and, in order to emphasize the economical character of this invention, let it be assumed—by way of an initial example—that the shingles 7, shown in Figs. I-III, are severed from a continuous sheet by means of a rotary drum cutter according to known practice.

Now it will be observed that each individual shingle 7 is of a configuration affording a rectangular upper portion 8 bounded by the top edge 9 and parallel side edges 10, 10. The lower portion 11 of each shingle 7 is of angular contour and point-down pattern; or, more specifically, said lower portion 11 comprises divergent edges 12, 12 directed preferably—though not essentially—at right angles to each other while affording a tip 13 conveniently creased at 14 for retroversion, and for a purpose later on more particularly referred to. At this juncture let it be assumed that the shingles 7 are severed from a twenty-two and five-eighths inch wide sheet with the linear dimension of the top edge 9, nineteen and three-quarter inches, and the medial dimension—indicated by the dot-and-dash line "a" in Fig. III—sixteen and one-quarter 95 100 inches.

5 inches, which gives the side edges 10, 10 a six and three-eighth inch dimension. Shingles 7 cut in accordance with the dimensions and outline above set forth will result in the divergent edges 12, 12 being each fourteen 10 inches long; or, in other words, if shingles 7 are cut from a twenty-two and five-eighth inch continuous sheet I produce what may be termed one-ply fourteen-inch shingles with literally no wastage of material whatsoever, 15 save the initial and terminal angular scraps; as will be readily appreciated on an examination of the dotted lines "b" about Fig. III.

15 Figs. V and VI illustrate, substantially to scale, forms of my invention cut from thirty-seven inch and twenty-five inch (or fifty inch) continuous sheet material respectively, and in view of their close similitude—except in relative dimensions—the reference numerals 20 applied thereto correspond with those employed in the preceding description; while further detailed explanation is deemed unnecessary, save to state that said specific types respectively furnish single and double ply 25 twelve inch shingles.

30 In making shingles 7 of proper size to afford a complete two-ply covering the most desirable results will be attained by omitting the mineralized surfacing from the upper part 15 of the rectangular portion 8, as shown in Figs. IV and VI. Omitting the mineralized surfacing in this manner tends to cause the shingles 7, when laid, to adhere together more completely than would be the case if 35 the entire top surface were completely covered. It will of course be readily understood that the continuous sheet material from which the just described type of shingles are cut will be manufactured with the running 40 edges free of mineral surfacing, or with parallel paths not coated with such surfacing.

45 Fig. VI illustrates, substantially to scale, a two-ply type of shingle 7 in accordance with this invention, the same being cut from thirty-one and seven-eighths wide material; whereas the form shown by Fig. III is severed from either twenty-two and five-eighths inch—or forty-five and one-quarter inch—wide sheet material. Both of the types just referred to 50 are known in the trade as fourteen inch shingles.

55 Either type of shingle hereinbefore described is so simple that further detailed explanation is deemed unnecessary beyond stating that shingles 7 so configured will be readily applied to the guide lines 16 on a roof or other surface 17—due to the rectangular upper formation 8—and attached with nails (not shown) in the conventional manner. 60 Similarly the key wires 18 will be inserted in the well known manner, while the tips 13 are creased along a line 14 parallel with the fiber formation of the felt material which tends to reduce cracking along said crease or bend. 65 Obviously I may cut lengths of the material

to include a multiplicity of the shingles patterned along the lines described as will be readily apparent to those acquainted with the art.

70 From the foregoing it is thought that my invention will be fully understood but among the inherent advantages attention is particularly directed to its utilitarian and economical character, whereby a roof or other surface may be completely covered with a one-hundred per cent two-ply thickness of shingle material thereby affording a durable and effective weather protection. Furthermore it will be apparent that pro rata, while shingles embodying this invention utilize 75 somewhat more material per square laid, such increase is negligible when contracted with the economy effected in cutting, as well as the saving in time and labor involved during laying. Again it will be readily appreciated that by laying my improved shingles as a two-ply facing for a roof or other structure, rain, sleet, snow and the like cannot drive inwardly between the respective units and successive 80 rows thereby causing leaks; while surfaces covered by the novel configured shingles illustrated will be accurately lined and give 85 durable service.

90 Although I have shown and specifically detailed certain essentials of shape as pre-requisites in carrying my invention into effect, it will be understood I am not necessarily limited to the precise patterns illustrated, as various minor changes and modifications may be made, within the scope of the subjoined 95 claims, without departing from the spirit of my invention or sacrificing any of its advantages.

100 Having thus described my invention, I claim:—

105 1. A surface covering composed of individual mineral-surfaced flexible shingles adapted to be laid in staggered relation; each said shingle having a rectangular upper portion which—when butted—form a continuous 110 material thickness along each row, said rectangular upper portions being in part devoid of mineral surfacing so that the successively laid rows of shingles can firmly adhere into a substantially integral mass, and each said shingle having a right-angled point-down 115 end with the tip retroverted to seat wholly co-planar between the merging edges of an underlying pair of abutting shingles.

120 2. In a surface covering, a first row of shingles, each of which consists of a lower portion and an upper portion, the upper portion having parallel side edges contacting substantially throughout their extent with the side edges of the upper portions of adjacent shingles, the adjacent side edges of the lower portions of adjacent shingles being shaped to 125 form pockets, and a second row of similar shingles overlapping the first row, the shingles of said second row being provided with 130

tabs at their lower edges, said tabs being turned under the shingles of the second row and lying within the said pockets in the plane of the shingles of the first row.

3. In a surface covering, a first row of shingles, each of which consists of a lower portion and an upper portion, the upper portion having parallel side edges contacting substantially throughout their extent with the side edges of the upper portions of adjacent shingles, the adjacent side edges of the lower portions of adjacent shingles being shaped to form pockets, a second row of similar shingles overlapping the first row, the shingles of said second row being provided with tabs at their lower edges, said tabs being turned under the shingles of the second row and lying within the said pockets in the plane of the shingles of the first row, and means for retaining said tabs within the plane of the shingles of the first row.

4. A surface covering composed of individual flexible shingles adapted to be laid in staggered relation, each of said shingles having a rectangular upper portion which when the shingles are abutted will form a continuous material thickness along each row and each of said shingles having an angular point-down end with the tip retroverted to seat wholly coplanar between the merging edges of an underlying pair of abutting shingles.

5. A surface covering composed of individual flexible shingles adapted to be laid in staggered relation, each of said shingles having a rectangular upper portion which when the shingles are abutted will form a continuous material thickness along each row and each of said shingles having an angular point-down end with the tip retroverted to seat wholly coplanar between the merging edges of an underlying pair of abutting shingles, said shingles being of dimensions to afford a surface covering of at least two-ply thickness throughout.

45 In testimony whereof, I have hereunto signed my name at Maurer, New Jersey, this 18th day of September, 1924.

JOHN HENRY WELLER.
